Primary Examiner — Catheri Oliver-Garcia(74) *Attorney, Agent, or Firm* — Robert C. Montgomery; Montgomery Patent & Design(57) **CLAIM**

The ornamental design for a holster belt, as shown and described.

DESCRIPTION

FIG. 1 is a front perspective view of the holster belt showing my new design;

FIG. 2 is a rear perspective view thereof;

FIG. 3 is a front elevation view thereof;

FIG. 4 is a back elevation view thereof;

FIG. 5 is a left side view thereof;

FIG. 6 is a right side view thereof;

FIG. 7 is a top plan view thereof; and,

FIG. 8 is a bottom plan view thereof.

The dashed lines indicate boundary areas and form no part of the claimed design.
